(57) **CLAIM**

The ornamental design for an image scope, as shown and described.

DESCRIPTION

FIG. 1 is a perspective view of my image scope;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 6A is a magnified view of a portion of FIG. 6;

FIG. 7 is a bottom view thereof; and,

FIG. 8 is an exploded perspective view thereof.

The broken line portions of the disclosure are included for the purpose of illustrating environment and form no part of the claimed design.
